UNITED STATES PATENT OFFICE.

SAMUEL POLLOCK, OF ZANESVILLE, OHIO.

FLAT-IRON.

1,072,257.

Specification of Letters Patent.

Patented Sept. 2, 1913.

Application filed February 17, 1913. Serial No. 743,945.

To all whom it may concern:

Be it known that I, SAMUEL POLLOCK, a citizen of the United States, residing at Zanesville, in the county of Muskingum and State of Ohio, have invented certain new and useful Improvements in Flat-Irons, of which the following is a specification.

My invention relates to flat irons and has particular reference to an apparatus of this character provided with means for generating steam and properly applying the same to the garment or other article being pressed.

An important object of this invention is to provide a flat iron of the above mentioned character, the parts of the steam boiler and gas burner being entirely disposed within the shell or body portion of the iron, and arranged therein in a compact manner so that the same will occupy the minimum amount of space and the maximum amount of steam generated by the operation of the burner.

A further object of this invention is to provide a flat iron of the above mentioned character, which is simple in construction, cheap to manufacture, strong and durable.

Other objects and advantages of this invention will be apparent during the course of the following description.

In the accompanying drawings forming a part of this specification and in which like numerals are employed to designate like parts throughout the same, Figure 1 is a plan view of the steam boiler included in the iron, the top plate and burner being removed, Fig. 2 is a central vertical longitudinal sectional view through the iron, Fig. 3 is a transverse sectional view taken on line 3-3 of Fig. 2, and, Fig. 4 is a horizontal sectional view taken on line 4-4 of Fig. 2.

In the drawings, wherein for the purpose of illustration, I have shown a preferred embodiment of my invention, the numeral 5 designates the body portion of the iron, which is preferably formed of a copper casting. The upper end of this body portion is formed open and is normally closed by a top plate 6, preferably formed of cast iron. At its upper end the body portion 5 is provided with relatively large openings 5^a, through which pass the products of combustion from a burner to be described. The burner is also lit by inserting a match through one of these openings. A strip

or sheet of asbestos 7 or other heat resisting material is interposed between the top plate 6 and the body portion 5, these parts being held together by stove bolts or screws 8, as shown. Connected with the top plate 6 are upstanding arms 9, carrying at their upper ends a handle 10, which is preferably formed of wood. The lower side of the body portion 5 is in the form of a plate 11, provided with longitudinal and transverse passages or bores 12 and 13. These passages intersect and are thereby placed in free communication. The outer ends of the passages are screw-threaded, for receiving plugs 14.

Disposed upon the outer surface of the plate 11 is a sole plate 15, connected therewith by any suitable means. This sole plate has its engaging surface perfectly flat so that all portions thereof are disposed in the same plane, the same being smooth or polished. This sole plate is preferably formed of good close grained gray cast iron, which will finish well and wear smooth. After the sole plate has been connected with the plate 11, steam outlet ports 16 are drilled through the plate 15 and into the plate 11 and lead into the transverse passages 13. It has been found by experience that these outlet ports must be comparatively small in diameter, the most satisfactory results being obtainable by having them 3/64ths of an inch in diameter. These steam outlet ports are preferably transversely spaced 3/16ths of an inch apart.

The numeral 18 designates a boiler or steam generator as a whole, the same being formed of a coiled pipe having upper and lower turns 19 and 20. This coiled pipe is preferably a copper pipe having an internal diameter of 1/8th of an inch. The upper and lower turns 19 and 20 are disposed in different horizontal planes and extend longitudinally within the body portion 5, as shown. The free end of the lower turn 20 is screw-threaded, as shown at 21, for connection with a water supply hose or the like (not shown). The innermost upper turn 19 is centrally arranged within the body portion 5 and is bent at a right angle to form a depending portion 22, having its lower end provided with an outwardly extending flange 23. This lower flanged end of the depending portion 22 is mounted within an apertured upstanding boss 24 formed upon the plate 11. This boss 24 is

internally screw-threaded for engagement with a clamping nut 25, the lower end of which engages the flange 23, to securely hold the same in place and form a steam-tight connection. If necessary, a packing ring 26 may be interposed between the flange 23 and the wall at the bottom of the aperture in the boss 24. The depending portion 22 has free communication with the central longitudinal passage 12 and hence with all of the passages 13, through the medium of a port or opening 27.

Mounted within the lower portion of the body portion 5 below the boiler or steam generator 18 is an open tubular burner 28 preferably of the shape shown. This open tubular burner 28 receives therethrough the depending portion 22 of the steam supply pipe. This generator is adapted to use gas as a fuel, either natural or artificial gas or other fuel. The outer end 29 of the burner 28 extends through an opening in the end wall of the body portion 5 and is connected with a fuel supply pipe (not shown) through the medium of a coupling 30. As more clearly shown in Figs. 2 and 3, the burner 28 (which is in the form of a pipe) is provided with openings or perforations 31, 32, 33, 34, 35, and 36, as shown. These openings are preferably made 1/16th of an inch in diameter. The openings 34 and 35 are preferably arranged at an angle of 45° with relation to the plate 11 and the opening 36 is perpendicular with relation thereto. The function in this angular arrangement of the openings 34, 35 and 36 is to direct the flame so that the same will properly impinge against the plate 11 to heat the same. The opening 33 is disposed at an angle of 45° to the horizontal, the opening 31 is perpendicular to the horizontal and the opening 32 is disposed at an angle of 60° to the horizontal. I have found by this angular arrangement of the openings 31, 32 and 33, that the flame passing therethrough will impinge against or heat the lower turns 20 of the boiler 18 in a most efficient manner.

The operation of the iron is as follows: The water is continuously supplied to the lower turns 20 of the boiler 18 from the hose or pipe (not shown). This hose or pipe is provided with a check valve for preventing the back flow of the water or steam.

The burner 28 being lit, as steam is generated in the lower turns 20, the same will pass upwardly into the upper turns 19 within which the steam is further heated, prior to its passage through the depending portion 22. This steam now passes through the depending portion 22 and discharges into the passages 12 and 13. In these passages the steam is further heated or superheated, while the same is discharging through the outlet ports 16. The object in providing the plate 11 with the passages 12 and 13 instead of having an integral open space or chamber formed therein, is to lessen the heating area which is engaged by the steam therein. It is obvious that the gas burner will provide flames which extend upwardly and downwardly at the proper angles to efficiently heat the boiler 18 and the plate 11.

It is to be understood that the form of my invention herewith shown and described is to be taken as a preferred example of the same, and that certain changes in the shape, size and arrangement of parts may be resorted to without departing from the spirit of the invention or the scope of the subjoined claim.

Having thus fully described my invention, I claim:—

In a flat iron of the character described, a body portion including a lower plate provided with communicating longitudinal and transverse steam receiving passages which discharge through steam outlet ports, a boiler mounted within the upper portion of the body portion and formed of a coiled pipe including lower intake turns and upper steam generating turns having their discharge end bent downwardly for forming a depending portion having communication with the longitudinal and transverse steam receiving passages, and an open tubular burner mounted within the body portion between the boiler and lower plate and receiving therethrough the depending portion of the boiler and provided with perforations upon its upper and lower sides.

In testimony whereof I affix my signature in presence of two witnesses.

SAMUEL POLLOCK.
